UNITED STATES PATENT OFFICE.

ARTHUR J. HOWARD, OF MALDEN, MASSACHUSETTS, ASSIGNOR TO THE
WIRE GRIP FASTENING COMPANY, OF CHICAGO, ILLINOIS.

DESIGN FOR A NAIL OR SLUG.

SPECIFICATION forming part of Design No. 24,760, dated October 15, 1895.

Application filed September 9, 1895. Serial No. 562,012. Term of patent 14 years.

To all whom it may concern:

Be it known that I, ARTHUR J. HOWARD, of Malden, in the county of Middlesex and State of Massachusetts, have invented and produced 5 a certain new and original Design for a Nail or Slug for Boot or Shoe Heels, of which the following is a specification, reference being had to the accompanying drawings, forming a part thereof.

10 Figure 1 is an isometric view of a nail or slug, showing my design; and Fig. 2 is an end view thereof.

15 The leading feature of my design for a nail or slug consists in a thin flat body having a central enlarged portion extending longitudinally of the body, and beyond which the latter projects at opposite parts.

The body *b* of the nail or slug is thin and flat, while it is enlarged centrally at *b'*, the enlargement extending longitudinally of the 20 body, which projects beyond it at opposite sides.

I claim—

The design for a nail or slug substantially as set forth.

25 In testimony whereof I have signed my name to this specification in the presence of two subscribing witnesses.

ARTHUR J. HOWARD.
